AUXILIARY HEATING DEVICE

Filed Jan. 14, 1929

UNITED STATES PATENT OFFICE.

LUTIE KERN, OF LAWRENCE, KANSAS.

AUXILIARY HEATING DEVICE.

Application filed January 14, 1929. Serial No. 332,426.

My invention relates to furnaces, and more particularly to damper-like valves for controlling the flow of products of combustion from the furnace to the chimney, the 5 principal objects of the invention being to facilitate the operation of a valve of this character, and to reduce the size of the valve housing.

The invention is particularly devised for 10 selective restriction of flow of gases from a furnace into one or another of a plurality of conduits, for example for flow through an auxiliary heater or directly to the chimney. The hot gases tend to cause expansion of the 15 valve members, whereby the operation of the valve may be impeded or prevented. A further object of the invention therefore is to provide a valve that will operate efficiently and irrespective of effects of heat thereon.

20 A housing for a valve for controlling the flow of gases must usually be positioned at the smoke outlet of the furnace, the location of an auxiliary heater is determined by factors such as the position of the chimney 25 inlet which are not under the control of the person providing the installation, and crowded conditions in a basement may render it difficult or impossible to relate the valve housing properly to the furnace and auxiliary heater for most efficient operation of the 30 installation.

Further objects of my invention therefore are to provide a valve and valve housing that may be adjusted to the relatively fixed positions of the furnace, chimney and auxiliary heater for proper and easily effected control of the flow of gases, and whereby the most efficient operation of the installation may be promoted.

40 In accomplishing these and other objects of the invention, I have provided improved details of structure, the preferred forms of which are illustrated in the accompanying drawings, wherein:

45 Fig. 1 is a perspective view of a portion of a basement and a heating plant having my improved valve connected to the furnace for controlling flow of gas selectively through an auxiliary heater or directly to the chimney.

50 Fig. 2 is an enlarged vertical longitudinal section of the valve and valve housing, and adjacent portion of a conduit connected to the housing and partly broken away.

Fig. 3 is a detail perspective view of the 55 valve-supporting bolt and plate.

Referring in detail to the drawings:

1 designates a furnace having a short smoke outlet flange 2, 3 a chimney, 4 an auxiliary heater box, 5 a direct conduit for direct flow of gases from the furnace to the chimney, 6 an outlet pipe from the auxiliary heater toward the chimney connected to the direct conduit at 7, and 8 a by-passing pipe for conducting gases from the furnace into 65 the auxiliary heater.

The auxiliary heater may be of any preferred construction, for example such as the heater disclosed in my co-pending application, Serial No. 268,421, to which the invention presently described is particularly adapted, the pipe 8 extending angularly and having an elbow 9 connected into the end wall 10 of the heater adjacent its lower end, and an elbow 11 adapted for connection into 70 the device presently described for controlling the flow of products of combustion.

75 My present invention includes a housing 12 comprising preferably a metal box including side walls 13 and 14 having centrally located openings 15, and end walls 16 and 17 having similar centrally located openings 18, and a top or cover 19 having a longitudinal slot 20 for a purpose later described. The axes of the openings 15 and 18 are preferably in the same plane. The lower edges of the walls 13, 14 and 17 are provided with slide-supporting flanges 21 and ribs 22 forming grooves 23 and the end wall 16 is shortened for admitting to the grooves a sliding plate 24 forming the bottom of the housing and which may be removed for access to the inside of the housing for cleaning the same and for other purposes presently disclosed.

80 At each opening 15 and 18 is an annular flange 25 projecting outwardly from the housing to receive the furnace outlet flange 2, the direct conduit 5, the elbow 11 of the by-passing conduit, or a cap 26 for sealing an opening in which no pipe is positioned, 85 whereby gases from the furnace will be conducted into the housing for controlled flow into the auxiliary heater or directly to the chimney.

90 In the illustrated use of the invention, the auxiliary heater pipe 8 is connected to the housing at the opening in the side wall 14, in alignment with the furnace outlet flange 2

which is connected to the flange of the side wall 13, the direct conduit is connected to the end wall 17, and the cap 26 is mounted over the opening in the end wall 16 and opposite to that with which the direct conduit communicates.

Slidably mounted on the cover 19 and closing the slot is a plate 27 and a stem or bolt 28 secured to the plate extends through the slot and is freely movable therein for supporting a plate or valve 29 from the cover for movement into and out of engagement with the end wall 17 to obstruct and control flow of gases through the direct flow conduit 5, and incidentally control the flow of gases into the auxiliary heater, since the gases will tend to flow through the direct conduit when the valve is open.

The valve 29 may be a disk adapted to cover the opening and move freely in the housing. A boss or lug 30 is provided on the back of the disk, the bolt 28 passes through the lug and is adjustably latched thereto by nuts 31 and 32 threaded on the bolt whereby the relation of the disk to the opening may be adjusted.

The bolt and disk are supported from the housing-supported sliding plate 27 by a head 33 which may be a nut, and a nut 34 threaded on the bolt is countersunk in a recess 35 of the plate so that it may slide over the cover and attach the plate to the bolt with relative rigidity.

Spaced guide rails 36 are further mounted on the cover to retain the plate 27 in a rectilinear path, and assure the closing of the slot by the plate.

The ends of the slot 20 are equally spaced from the opposite end edges of the cover, whereby the valve may be reversed and may be moved into engagement with the opening in the end wall 16 to close the same.

A chain 37 may be secured to the upper end 38 of the bolt, and passed over pulleys 39 and 40 mounted on brackets 41 and 42 secured to the housing, and aligned with the bolt, and passed over pulleys such as 43 and 44 supported from rafters 45 of the basement, to provide a loop 46 conveniently located, for example at the furnace door, for operating the valve.

When a plurality of conduits are to be installed for passage of gases from a furnace to the chimney, for example when an auxiliary heater is provided, the auxiliary heater may be mounted in any desired relation to the furnace. The valve housing may then be mounted on the outlet flange of the furnace with the pipe engaging the annular flange in one of the side walls of the housing, for flow of gases from the furnace to the housing; an elbow may be mounted on the flange of the opposite side wall for connecting the housing to the auxiliary heater, the direct flow conduit may be connected to

either one of the end walls, and a cap may be installed on the opposite end wall to close the housing.

The direct flow conduit will be mounted on the end wall which is available in view of the preferred or accessible positions on the conduit. The valve may be rotated on the bolt so that its face is presented to the end wall with which the direct outlet pipe is connected, and the sliding plate may then be moved by means of the chain into and out of engagement with said end wall to control flow of gases therethrough.

Because of the relative shallowness of the housing, due to the provision of openings centrally of the housing walls, a relatively light weight housing may be formed that occupies a small amount of the restricted space adjacent a furnace in a basement.

The valve may be mounted in the housing after the latter is connected to the several pipes, the sliding bottom being withdrawn for access to the housing, the bolt being inserted through the slot and the disk valve adjusted thereon.

The vertical walls of the housing may be short, because of the character of the valve controlling the flow of gases, and the means for operating it, and contrasting for example with a housing having vertically aligned openings in one wall to receive the direct flow conduit and the pipe leading to the auxiliary heater.

The supporting plate slidable over the cover of the valve housing closes the slot and is easily operable through the chain.

The slot is substantially wider than the diameter of the valve-supporting bolt, so that expansion of the parts due to heat of gases passing from the furnace will not cause the bolt to bind in the slot.

What I claim and desire to secure by Letters Patent is:

1. In combination with a furnace having a smoke outlet, and a plurality of smoke conduits, a housing connected to the smoke outlet and the conduits and having a slot, a valve in the housing adapted to close one of the conduits, and means including a bolt slidable in the slot for moving the valve.

2. In combination with a furnace having an outlet for products of combustion, a plurality of conduits, a slotted housing connected to the outlet and the conduits, a stem extending through the slot of the housing and slidable therein, and a disk adjustably mounted on the stem within the housing and movable into closing relation with one of the conduits.

3. In combination with a furnace having an outlet for products of combustion, an auxiliary heater, and a chimney, a valve housing including similar side and end walls having similar openings, means connecting the outlet with one of said walls for flow

- of products of combustion from the furnace into the housing, a pipe mounted in the opening of another of said walls and connecting the housing with the auxiliary heater, a conduit mounted in the opening of another of said walls and connected to the chimney, and means movable in the housing for controlling flow of products of combustion from the housing into said conduit.
- 10 4. A device of the character described for controlling flow of fluids into a plurality of conduits, comprising in combination with conduits, a housing including walls having outlets into said conduits, a valve bodily movable in the housing into engagement with one of said walls to close the outlet therein, the housing including a wall having a slot parallel to the axis of said valved outlet, and a stem on the valve slidable in the 20 slot for operating the valve.
5. In a device of the character described for controlling flow of gases from a furnace outlet pipe, in combination with an outlet pipe and a plurality of conduits, a housing comprising opposite side walls having registering openings, the outlet pipe and one of said conduits being connected to said side walls in alignment at said openings, the housing having end walls provided with
- registering openings for selective mounting of another of said conduits in one of said end walls for communication with the housing, a valve movable in the housing for controlling the flow of gases through said selected end wall into said other conduit, the housing having a cover provided with a slot, a plate slidable on the cover and closing the slot, and a stem secured to the plate and extending through the slot for supporting the valve, and movable longitudinally of the 30 slot for operating the valve.
6. In a device of the character described for controlling flow of gases from a furnace to a chimney, a housing having an inlet from the furnace, a direct flow outlet toward the chimney, and a by-passing flow outlet, a cover for the housing having an elongated slot parallel to the axis of the direct flow outlet, a threaded stem extending in the slot, a valve adjustably mounted on the stem and bodily movable toward and away from the direct flow outlet, and means for supporting the valve including a plate connected to the stem and slidable on the cover, said plate being adapted to close the slot. 55

In testimony whereof I affix my signature.

LUTIE KERN.
